UNITED STATES PATENT OFFICE.

ARTHUR C. LA MAY, OF ROCHESTER, NEW YORK, ASSIGNOR TO TODD PROTECTOGRAPH COMPANY, OF ROCHESTER, NEW YORK, A CORPORATION OF NEW YORK.

CHECK-WRITER.

1,364,941.

Specification of Letters Patent. Patented Jan. 11, 1921.

Application filed June 19, 1916. Serial No. 104,606.

To all whom it may concern:

Be it known that I, ARTHUR C. LA MAY, a citizen of the United States, residing at Rochester, in the county of Monroe and State of New York, have invented certain new and useful Improvements in Check-Writers, of which the following is a specification.

The object of this invention is to provide a check writer of a new and improved type.

This and other objects of the invention will be illustrated in the drawings, described in the specification and pointed out in the claims at the end thereof.

15 In the drawings,

Figure 1 is a top plan view of the machine with the type carrier in normal position.

Fig. 2 is a top plan view of the machine with the type carrier given a quarter turn.

20 Fig. 3 is a vertical section through the machine on the line 3^x—3^x of Fig. 1, with the end of the type carrier partly broken away.

Fig. 4 is a detail perspective view of the mechanisms for raising the platen and for 25 moving the inking roll into and out of operative position.

Fig. 5 is a vertical section through the machine on the line 5^x—5^x of Fig. 3.

Fig. 6 is a side elevation of the ink supply 30 roller partly in section, the section being taken on the line 6^x—6^x of Fig. 2.

Fig. 7 is a detail perspective view of one of the buttons for shifting the type bars.

Fig. 8 is a perspective view showing a 35 modified form of the roller platen and driving mechanism therefor.

Fig. 9 is a longitudinal section through the platen, the section being taken on the line 9^x—9^x of Fig. 8.

40 Fig. 10 is a detail perspective view of the type bar looking at it from the back.

Fig. 11 is a longitudinal section of a modified form of my improved check writer.

Fig. 12 is a vertical section on the line 45 11^x—11^x of Fig. 11.

In the drawings reference numeral 1 indicates the work bed or base plate on which are fastened the uprights 2 and 3 by screws 4 which are formed integral with the feet 5. 50 These feet 5 are hollow or recessed at the bottom to receive the rubber pads 6.

The uprights 2 and 3 are tied together at their tops by the rods 7 and 8. The rod 7 projects beyond the upright 2 and forms a

stop or holding device 10 for the handle 9 55 that will presently be described. Mounted to rotate in the uprights 2 and 3 is the shaft 11. To the outer end of this shaft the handle 9 is keyed. On this shaft and between the uprights 2 and 3 is keyed the type carrier 60 12. This type carrier consists preferably of two semicircular plates or webs 13 and 14, which plates are fastened together at regular intervals near the margin thereof by the rods 15—25. These rods have reduced 65 shouldered ends which go through the plates, the ends of some of these rods being riveted in place and others fastened by nuts.

Mounted to slide between these rods are the type bars 26, 27, etc. Each of these type 70 bars is made up of a type plate 37 (Fig. 10) fastened by soldering or other suitable means to the carrying plate 38. Each of the type plates 37 are engraved with various characters or lines of characters which the machine 75 is intended to print on the check. Each of the carrying plates 38 is made of a piece of sheet metal, the ends of which are bent up at right angles as shown at 39 and 40 in the sides of which are cut the semicircular recesses 41 and 42 with which recesses the carrying plate engages the rods 15 etc., between which they are mounted to slide.

Mounted between the rods 15 and 16 is the stationary type bar 26 (Fig. 2) on the type 85 plate of which is engraved a "*" or any other suitable character to mark the beginning or end of a line. This type bar 26 may be made short. The remaining type bars are long and are mounted to slide longitudinally, 90 axially of the carrier and each has space thereon for fourteen type forms for printing words or lines or characters as will now be described.

Between the rods 16 and 17 is mounted 95 the type bar 27 on the type plate of which is engraved the fourteen words "Fourteen, Fifteen, Sixteen, Seventeen, Eighteen, Nineteen, Twenty, Thirty, Forty, Fifty, Sixty, Seventy, Eighty, Ninety." On the type bar 100 28 is carried a type plate on which is engraved the thirteen consecutive words from "One" to "Thirteen" inclusive. On the type bar 29 is carried a type plate on which is engraved the word "Hundred," which word 105 may be placed thereon alone, in which case the type bar may be shortened or on which the word "Hundred" can be repeated in each

of the fourteen lines or on which the first word may be "Hundred" and thereafter other words may be used. On the type bar 30 is carried a type plate on which is engraved the same characters as appear on the type plate of the type bar 27.

On the type bar 31 is carried a type plate on which is engraved the words "One" to "Thirteen" inclusive similar to the type bar 28. On the type bar 32 is carried a type plate on which is engraved in the first line the word "Dollars" and on the next line the word "Dollar" and either of these words may be repeated on the remaining lines of the plate or the balance of the plate may be left blank, and the plate may be correspondingly shortened as so desired, or after the word "Dollar" and "Dollars" other words may be engraved thereon to denote foreign coins such as "Pounds," "Marks," etc.

On the type bar 33 is carried a type plate on which is engraved the fourteen words "Fourteen" to "Ninety" inclusive similar to the words engraved on the type bar 27. On the type bar 34 is carried a type plate on which is engraved the words "One" to "Thirteen" similar to the type bar 28. On the type bar 35 is carried a type plate on which is engraved the word "Cent" and "Cents" in two lines. The rest of this plate may be left blank and the plate may be correspondingly shortened or in the remaining spaces words may be used to indicate coins of foreign denominations.

In the machine illustrated in these drawings one stationary type plate is used and nine moving type plates are used on the type carrier. By making the type plates and bars narrower or by increasing the diameter of the type carrier the number of these type plates and bars may be increased, and by making the type plates and bars wider or the diameter of the carrier smaller the number of these type plates and bars may be diminished. In the machine illustrated in the drawings the type carrier has a diameter of about eight inches.

The machine is arranged so that only one line of each of these type bars will print at a time and only that line will be printed that is brought into line with the roller platen 43 which platen is a little wider than one of the lines of type on the type bar. For the purpose of moving any particular line of either type bar or of a series of type bars into line with the platen, a pointer or index 44 is connected to each of these type bars as will now be described.

Between the upturned ends 39 and 40 of each of the carrying plates 38 is mounted a rod 45 on which is mounted a yoke or frame 46, the yoke being free to swing on this rod.

The yoke 46 and carrier plate 38 are adjustable relative to each other by the lock nuts 47 and 48 which may be moved along

the rod 45 pushing the yoke ahead of them against the spring 49^a which will be compressed by the yoke, the spring serving to take up the lost motion that would otherwise exist between the yoke and the rod or carrier. At the upper end the yoke 46 is turned over at 47^a to form a bracket which is perforated to receive the stem 48^a on the upper end of which is carried the button 49 by which the yoke and type bar are moved by the operator of the machine. Below the bracket 47^a the yoke 46 is perforated to receive an eye bolt 50, the eye of which bolt is threaded with a female thread to receive the threaded end of the stem 48^a. By this the stem is supported and held in place. At the upper end of the yoke 46 is provided a spring pointer 44, which pointer is clamped on the yoke by the eye bolt 50, and by the second bolt 52.

To the top of the type carrier is fastened a slotted key board 53 in which key board is provided nine long slots as shown in Fig. 1. In each of these slots one of the stems 48^a and springs 44 are adapted to slide with the yoke. The key board on one side of each of these slots is ruled with a series of lines that are evenly spaced apart and opposite each of these lines on the other side of the slot is cut a series of recesses. The spring pointer is adapted to point to or cover each of the lines in turn and the force of the spring of the pointer will force the stem 48^a back into the recess on the other side of the slot and center the stem and pointer and type bar in correct position.

The consecutive slots and the pointer thereon are arranged from left to right on the key board to represent ten thousands, thousands, hundreds, tens, units, dollars, tens, units and cents so that a check written by this machine would read for example: *Thirty six hundred twenty six dollars twenty five cents. The machine so arranged will write checks up to but not including 110 ten-thousand dollars.

In Fig. 1 I have shown a modification of the key board by which the machine can be adapted to write to but not including one million dollars. I have shown at the top of the key board in dotted lines four short slots in which pointers and buttons will be mounted to travel, which buttons will be connected to type bars on the type carrier. These buttons and type bars will be in addition to those heretofore described so that in this latter case the machine will be provided with thirteen buttons and type bars instead of only nine buttons and type bars. In this latter case the rods 15, etc., will be spaced closer together and there will be fifteen of them instead of the eleven illustrated, and the type bars will be made narrower and increased to fourteen and the type or words will be condensed to correspond. With the 130

machine so arranged a check may be written with a legend for example as follows: "Nine hundred fifty-two thousand six hundred twenty one dollars twenty five cents.

5 In this legend four words have been underscored to indicate that they will be printed by type carriers that are controlled by the upper row of buttons while the other 10 words will be printed by type carriers controlled by the lower row of buttons. The type carriers controlled by the buttons of the upper row will have a short movement corresponding to the length of the slot and these type carriers need carry but a single 15 word each and need be capable of movement only between two spaces so that it will either print the word or will be blank or inoperative. The nine type bars controlled by 20 the lower buttons will in the modified form of machine have the characters thereon that correspond to the characters on the type bars 28, 27, 28, 28, 27, 28, 27, 28 arranged in the foregoing order followed by the word 25 "Cents."

The first and fourth type bars corresponding to 28 need only have the words from "One" to "Nine" thereon but if the remaining words are included on the first bar then some checks over one "million" can be 30 written. If the remaining words are included on the fourth bar checks may be written in either of two ways as for example "One thousand two hundred" or "Twelve 35 hundred."

The key board 53 is fastened in place by the screws 60 which make threaded engagement with the bars 15 and 25.

By moving the various pointers to the 40 positions desired the type bars are moved so that the selected lines of type are brought into alinement with each other circumferentially of the carrier so that on the rotation of the carrier the check will be printed with 45 the words or characters selected.

When the type carrier is revolved the 50 check is pressed against the words or type characters on the type bars by the roller platen 43 and the operation of this platen 55 on the rotation of the type carrier will now be described.

Underneath the base the shaft 61 is mounted to oscillate. This shaft at one end is mounted to rock in a boss 62 and at the 60 other end is mounted to rock in a flange 63 on the side of the base.

The bosses 65 and 66 are also provided underneath the base plate in which the shaft 64 is mounted to rock, which shaft is parallel to the shaft 61. On the shaft 64 is keyed the platen yoke 67 which at its forward end carries the platen roller 43 and at its rear end is provided with a finger which is engaged by a roller 68 carried by a 65 yoke 69 keyed to the shaft 61. In the fin-

ger on the end of the platen yoke 67 is carried a screw 70 which makes contact with the roller 68. This screw may be turned up or down to regulate the depth of the embossing or printing of the platen roller 70 43. On each of the shafts 61 and 64 are provided screws or pins 71 and 72 between which the tension spring 73 is stretched, which spring serves to hold the roller 68 normally against the base plate 1 and serves 75 to hold the finger of the yoke 67 up against the roller 68. A lock nut 74 surrounds the screw 70 and serves to lock it in position. As shown in Fig. 5 lock nuts are also provided at each end of the shaft 64 by which 80 the shaft may be adjusted laterally for the purpose of correcting the position of the platen roller 43.

On the outer end of the shaft 61 is keyed an arm 75 which has a boss 76 therein on 85 which is mounted a screw 77 that passes through the boss. A soft buffer 78 is interposed between the end of the screw and the base plate and makes contact with the base plate, by which the upward movement of 90 the arm 75 is limited. By turning the screw up or down the position of the buffer may be adjusted.

On the end of the arm 75 is provided a pawl 79 which engages the teeth 80 on the 95 type carrier. The arm is depressed thereby on the rotation of the type carrier. One tooth 80 is provided on the web 13 for each of the type bars. As the type carrier rotates in the direction indicated by the arrow 100 in Fig. 3 the pawl 79 rises into the recesses between the teeth due to the contraction of the spring 73 and is again pressed down by the next tooth. This depresses the roller 68 and causes the platen roller 43 to rise 105 pressing the check against the line of type presented by the type bar. The friction of the type on the check will cause the check to move forward and the platen roller 43 will turn. This platen may be made of soft 110

material as of rubber and the type faces used in connection therewith may be plain or grooved. Or the platen may be made of hard material as of metal and may have either a smooth surface or a toothed surface 115 and the type faces used with the hard platen may also be plain or grooved. By suitable selection of type faces and platen the check may be printed either plainly, or embossed or mutilated. If any particular type bar is placed in idle position so that a blank space thereon is in line with the platen roller 43 then the check will not be fed forward while that type bar is passing over the platen roller. 120

Neither will the check be fed forward after the type of each successive word has passed the platen roller and this will now be described.

It will be noticed that some of the words 130

on the type bars are very short such as "One," "Two" and "Six" and others are rather long such as "Seventeen."

Each of these words will feed the check 5 forward just the length of the word plus a spacing after each word of the line that will be substantially uniform, the length of which spacing will be controlled by one or more factors that will presently be explained.

It will also be understood that on the type bars the ends of the words are lined up in even column as shown in Fig. 2 and the 15 beginnings of the words are in uneven column. The ends of the words occur substantially in line with the end of the teeth 80 and after the end of the tooth 80 has passed the pawl 79 the pawl drops off into the recess and permits the platen roller 43 to be 20 drawn back by the spring 73 and out of engagement with the check.

The teeth 80 are each made as long as the longest words carried by the type bar placed adjacent thereto or a trifle longer than the 25 longest word. On the type bar 27 the longest word is "Seventeen" and on the type bar 28 the longest word is "Thirteen" which is a trifle shorter than the word "Seventeen" on the type bar 27. The "*" carried on the type 30 bar 26 is shorter than either of these consequently as appears in Fig. 3 the first tooth 80 at the left is quite short, the second tooth 80 is quite long while the third tooth is slightly shorter than the second, etc. To 35 correspond with this the rods 15, 16, 17, etc., will be unevenly spaced and the width of the carrier plates and type plates will vary correspondingly, this being done for the purpose of saving space on the machine, and 40 getting the largest number of rows of type on the one type carrier.

The feeding of the check both for the length of the words printed thereon and the spacing of the words is accomplished as 45 follows:

Below the type carrier is placed the curved guide plate 94 in which is cut the slot 95^A. The check is placed below this plate and above the platen roller. As the 50 type of each word approaches the roller platen 43 the tooth 80 lifts the platen. When the platen roller rises it springs a portion of the paper of the check through this opening and forces it against the type on the carrier 55 or holds it in position to be engaged by the type as it approaches. This of course distorts the paper. If the word is a long one the paper will begin to move forward immediately on the lifting of the platen roller, 60 that is, if the word is as long as the tooth, but if the word is a short one the platen roller will be lifted in advance of the approach of the type of the word so that there will be more or less of an interval through 65 which the first of the type must move before

it engages with the platen roller and during this interval the paper will remain at rest. As soon as the type engages with the platen roller the paper is fed forward positively.

If a soft platen roller is used the paper 70 will be embossed on the type and will therefore tend to adhere to the type and move with it after the roller is withdrawn. As soon as the type has passed the center of the platen roller the platen roller drops. When 75 the platen roller drops the paper of the check is relieved from the distortion imposed on it by the roller and the paper will straighten itself out and draw the raised portion down through the opening in the 80 guide plate and away from the type. If the paper is stopped instantly at this point there would be no spacing between the consecutive words. The movement of the carrier is continuous and the paper is stripped 85 from the type while both are moving and the paper is left free with its own momentum which carries it forward until its movement is arrested by the raising of the platen roller by the next tooth 80. It will thus be 90 seen that while the movement of the carrier is continuous the paper moves intermittently or by a series of jerks.

The normal rate of speed of the type carrier will produce a normal spacing between 95 the words. If the speed of the type carrier is increased the spacing between the words will be increased. By dropping the platen roller and stripping the paper from the type as above described the spacing between consecutive words is materially shortened because the driving force on the paper is removed. If the roller is not dropped at all the spaces between words will be materially lengthened.

The action of the pawl 79 may be varied as follows:

The pawl 79 is pivotally mounted at 81 in a yoke on the end of the arm 75 by which yoke its movement in one direction is 110 limited. Its movement in the opposite direction is limited by the adjusting screw 82 which may be turned in or out, which screw bears against the lower end of the pawl. By turning this screw in or out the pawl will 115 engage with the teeth earlier or later.

Pivoted on the end of the pawl 79 is a spacing block 83. A screw 84 is mounted in the solid part of the pawl, the end of which engages with the end of the 120 spacing block 83. By turning the screw the block may be adjusted out or in for the purpose of varying the thickness of the end of the pawl. By adjusting the block 83 the clearance between the end of the pawl and 125 the recess between the consecutive teeth may be varied at will. The thicker the end of the pawl is made the quicker the pawl will be lifted by the tooth and the quicker the platen roller 43 will be thrown into action. 130

As the pawl is solid and not adjustable on the opposite side any adjustment of the thickness of the pawl will not change the point at which the pawl will drop off at the 5 end of the tooth, but will change only the lifting of the pawl at the beginning of the tooth. By making the end of the pawl thicker the length of the space is decreased and by making the end of the pawl thinner 10 the length of the space is increased.

If the type carrier is turned in the reverse direction from that indicated by the arrow in Fig. 3 the pawl 79 will be thrown to the right and out of position for engaging 15 with the teeth 80 and thereafter if the type carrier is turned in either direction the platen roller 43 will not be raised, and consequently there will be no feed of the check. To put the pawl back into normal position 20 so that it will engage the teeth 80 and cause the platen roller 43 to raise, the link 85 is provided which passes through the flange on the base as shown in Fig. 3. On the end this link is provided with a button by which 25 it may be pushed in to place the pawl 79 in the normal position shown in Figs. 3 and 4.

The check is held in position by the guides 30 87 and 88. Each of these guides is mounted to slide independently of the other transversely on the base 1. The base is slotted with the slots 89, 90, 91 and 92. The guides 87 and 88 are each provided with blocks on the under side thereof which engage in these 35 slots and hold the guides to a movement of right angles thereto. Below the base these blocks are connected by a spring friction plate 93, such as is shown in dotted lines in Fig. 4. These guides 87 and 88 may be 40 shifted laterally so as to accommodate any width of check or so as to hold the check in any desired position so that the line will be printed on any desired part thereof.

Mounted rigidly in the frame below the 45 type carrier is the curved guide plate 94 between which and the base of the machine the check must pass. The check is inserted in the machine on the guides 87 and 88 and is drawn through the machine by the operation 50 of the type carrier and platen and is thrown out on the opposite side of the machine.

The plate 94 is supported by the rods 95 and 96 which extend through the uprights 55 2 and 3.

The rod 96 also serves as a partial support for the inking device which will now be described.

An ink supply roller 97 is provided which 60 consists of two cylinder heads 98 and 99 between which is clamped the sleeves 100 and 101, which sleeves are spaced apart by a felt washer 102 which is held between them. The cylinder heads 98 and 99 are held together by the tie rod 103 which makes

threaded engagement with the inner ends of the cylinder head. The sleeves 100 and 101 also make threaded engagement with the cylinder head so that they are held firmly in place thereby and by the tie rod 103. 70

By turning the cylinder heads 98 and 99 against each other the sleeves 100 and 101 are drawn together compressing the felt washer 102 and this in turn regulates the flow of ink through the washer, it being 75 understood that the ink is carried inside of the sleeves 100 and 101.

The outer ends of the cylinder heads 98 and 99 are provided with cup bearings, one of which engages the screw 104 and the 80 other engages the screw 105. The screw 105 is provided with a knurled head so that it may be easily turned out far enough to release the inking roller 97 and permit its removal from the machine. 85

The felt pad 102 is slightly larger in diameter than the sleeves 100 and 101. This pad makes contact with the ink distributing roller 106 which is mounted in suitable bearings on a platform 107 which is pinned on 90 the bar 96. See Fig. 4. The platform 107 is continued up around the ink supply roller 97 and forms a guard for the felt washer and protects the operator's hand or the check from coming into contact therewith. 95

When the carrier is in normal position as shown in Fig. 3, one of the type bars will make contact with the inking roller 106 and the adjustment of it will on that account be interfered with. For the purpose of holding the inking roller out of contact with any of the type bars while the carrier is in the position shown in Fig. 3, I provide as follows:

The platform 107 is pinned to the shaft 96 105 as shown in Fig. 4 and rocks therewith. On the end of the shaft 96 I provide a pawl 108 which is normally held raised by the spring 109. On the outside of the web 14 of the type carrier is mounted a pawl 110. When 110 the type carrier moves forward the pawl 110 will be thrown back and will not affect the position of the pawl 108 and the spring 109 by its expansion will raise the pawl 108 and the platform 107 and will hold the distributing roller 106 up in position to apply ink to the type. When the carrier is moved in the reverse direction, however, the pawl 110 will swing against the pin 111 and the pawl 110 will be held in position thereby for 120 depressing the pawl 108 and holding it down while the carrier stands in the position shown in Fig. 3. While in this position the ink roller will not make contact with any of the type bars and they can all be shifted or adjusted freely. 115 125

The handle 9 is mounted on a spring pressed pin 112 as shown in section in Fig. 5. This pin passes through a sleeve and through the end of the handle where it is 130

- fastened by a nut 115. A spring is compressed between the end of the sleeve and a shoulder on the pin 112. The expansion of the spring forces the pin to the right and into engagement with a socket or holding device 113 provided on the base. By drawing the handle out the pin is disengaged from the socket and the type carrier can be rotated.
- 10 When the check is inserted in the machine its forward movement is arrested by the pin 114 forming a presser foot or stop which projects through the base and against the plate 91. This pin is upturned from the end 15 of the crank 115 which is mounted to rock underneath the base. The other end of the crank turns up through the slot 116 and engages with the rim of the web 14. A spring 117 is provided on the crank which normally 20 holds the pin 114 raised in the position shown in Fig. 4, until the inclined end of the crank 115 is engaged by the rim of the web 14 which will turn it down and draw the pin 114 down through the base.
- 25 The semi-circular plate or web 14 may be notched similar to the semi-circular plate or web 13 so that the upwardly extending arm of the crank 115 which projects through the opening 116 will snap into these notches 30 and in turn allow the pin 114 to rise and press at certain intervals against the check while the check is passing through the machine. In this way the momentum of the check will be overcome at proper intervals 35 and a shorter spacing between the words printed on the check will be secured.
- The operation of the machine is as follows:
- The type carrier is first placed in the position shown in Fig. 3 and while in that inactive or resting position the buttons shown in Fig. 1 are adjusted. The type carrier is then swung from the position shown in Fig. 3 to the position shown in Fig. 2. In this 40 starting position the pin 112 in the handle will engage with the stop 10 and hold the carrier in the position shown in Fig. 2. In this position the pin 114 will be raised as shown in Fig. 4. The carrier is left in this 45 position and the check is then inserted on the guides 87 and 88, the forward movement of the check being arrested by the pin 114 shown in Fig. 4. The carrier is then turned forward to bring the type into engagement 50 with the check. Before the type reaches the check the pin 114 drops and as the type reaches the check the platen roller 43 is raised and between the type and the platen roller the check is fed through the machine and 55 printed and ejected on the other side.
- In Fig. 8 I have shown a modified form of a roller platen to be used for a substitute for the platen 43. This platen is made up of a series of saws 120 keyed on the shaft 121 and spaced apart by washers, the shaft 65 being driven through the universal joint 122 by a friction wheel 123 which is in turn driven by a friction wheel 124 which is in turn driven by the rim of the web 14. The platen or saws will thus be driven in the direction opposite to the feed of the check. The diameter of the friction wheel 123 will be considerably less than the diameter of the saws 120 so that the saws will move faster than the check and in the opposite direction. Each tooth will tear the paper and remove a part of it. To separate the check from the saws I provide the fingers 124^a which engage between the saws for the purpose of stripping the check therefrom. These fingers are pivoted at 125 on the platen yoke 67. At the top the fingers 124^a are curved convexly to make contact with the type. This type will bear against these fingers and between the fingers and the type the check will be fed, the type engaging with the check and causing it to slide over the fingers.
- The forward movement of the check will be governed by the speed of the type which 90 will move the check forward regardless of the faster movement of the saws in either the same or the reverse direction.
- As shown in Fig. 8 the saws will rotate backward while the type will carry the 95 check forward, but the gearing may be arranged to drive the saws forward instead and at a higher rate of speed than the check is moved by the type.
- It will also be understood that the thickness of the saws, washers and fingers in Figs. 8 and 9 is exaggerated, the saws each being in practice made about twenty-five thousandths of an inch in thickness, and the total width of the saw platen will be a little 100 more than the height of the letters on one line of type.
- As appears from Figs. 8 and 9 the fingers extend slightly above the saws. This will prevent the saws from engaging with the 110 type but the paper of the check where it is raised or embossed by the type will bulge down between the fingers so that it will be cut by the saws and will be more or less removed thereby.
- It will also be understood that grooved 115 type may be used in connection with this saw platen to increase the cutting of the check by the platen, in which case the grooves in the face of the type would come opposite to the fingers between the saws and the ridges in the face of the type would come opposite to the saws. The paper of the check will conform substantially to the face of the type and the ridges in the face 120 of the type will raise or bulge the paper in ridges higher than would be formed in the paper if flat faced type were used and the

paper in these ridges will be cut by the saws to a greater extent than if the face of the type were left flat.

The saws 120 and the fingers 124^a may also be heated in any suitable manner preferably by electricity so that when the check is drawn through between the platen and the type the teeth of the saws or fingers will scorch the paper where it is indented and this still further protects the impression against being changed.

As shown in Fig. 8, the platen may be provided with an electric heating coil so that the platen may be heated to scorch the paper when it comes in contact therewith.

In Figs. 11 and 12 I have shown a modification of my check writer which I will now describe.

In this modification I indicates the base 20 with a flange 130 provided thereon. In this flange is an opening 131. Fastened to this flange is the inner cylinder 132 which is stationary. Around this cylinder extends the circumferential teeth 133 with grooves 25 therebetween. In this cylinder is a series of slots 134 extending about two-thirds the length thereof. These slots extend transversely to the teeth 133. In these slots are mounted to slide the yokes 135. Connected 30 to each of these yokes is a rod 136 to the end of which is connected a button 137 which is mounted to slide in the slot 138 on the keyboard 139.

Surrounding the stationary cylinder 132 is the rotating cylinder 140. On this cylinder is carried a series of type bars 141. On the top of these bars are rows of types 35 142 containing words similar to the words on the type bars 27, 28, etc. In Fig. 11 one 40 of these type bars is shown in longitudinal section, with six rows of type thereon. By making the machine longer or the rows of type narrower any number of rows of type may be placed on each bar.

Underneath the type bars are the teeth 143, 143 with which engage other teeth provided on the yoke 135. These type bars 141 can be moved to different positions by the buttons 137 through the yokes 135. The 45 type bars must be positioned by the yokes so that the teeth 143 thereon will occur in alinement with the spaces between the teeth 133 on the stationary cylinder 132. When the various type bars have been properly 50 positioned the outer cylinder will be rotated by the handle 144 which projects outside of the casing 145. This handle 144 is mounted on the outer cylinder 141.

The type bars move with this cylinder. 55 They are locked against longitudinal movement by the engagement of the teeth 143 thereon with the teeth 133 on the stationary cylinder 132. The type bars will be carried around with the outer cylinder 141 as it

rotates and the teeth on the under side of 65 the type bars will ride between the teeth on the periphery of the inner cylinder which will prevent any disturbance of their alinement. While the outer cylinder is being rotated the check can be fed between it and 70 the roller platen and printed.

When the outer cylinder has made a complete revolution or returns to normal position the type bars can be again moved through the buttons 137 to other positions 75 upon which the operation of the machine can be repeated. The other features of the machine will be the same as the corresponding features in the machine above described.

I claim.

1. In a check writing machine a combination of a casing, a carrier mounted to rotate thereon, said carrier having substantially the shape of a half cylinder and having a flat top and round bottom, a keyboard 85 arranged on said flat top, type bars mounted to slide on said round bottom, and keys or pointers mounted to slide on said keyboard, said type bars being connected to said keys and moved thereby.

2. In a check writing machine the combination of a casing, a rotatable carrier mounted thereon, said carrier comprising a pair of segmental plates placed parallel to each other, a series of rods connecting said plates 95 and spacing said plates apart, and type bars each mounted to slide between successive rods to bring various type forms selectively to a common printing position in alinement with other selected type forms circumferentially of the carrier.

3. In a check writing machine the combination of a casing, a rotatable carrier mounted thereon, said carrier comprising a pair of segmental plates placed parallel 105 to each other, a series of rods connecting said plates and spacing said plates apart, type bars mounted to slide between successive rods, a key board mounted above said type bars, keys mounted to slide on said board, and connections between said type bars and said keys.

4. In a check writing machine the combination of a type bar having a plurality of independent type forms spaced from each 115 other longitudinally of the bar and grooves along the side thereof, a rotatable carrier having rods extending the length thereof on the periphery thereof, said type bar engaging with and being supported between 120 said rods, and grooves on the type bar engaging with the rods.

5. In a check writing machine the combination of a casing, a rotatable carrier mounted thereon, said carrier comprising a 125 pair of segmental plates placed parallel to each other, a series of rods connecting said plates and spacing said plates apart, type

- bars mounted to slide between successive rods, and a roller platen mounted below said carrier and capable of movement into and out of engagement with the periphery thereof.
6. In a check writing machine the combination of a casing, a rotatable carrier mounted thereon, said carrier comprising a pair of segmental plates placed parallel to each other, a series of rods connecting said plates and spacing said plates apart, type bars mounted to slide between successive rods, a roller platen mounted below said carrier and capable of movement into and out of engagement with the periphery thereof, and means for supporting a check between said roller platen and the periphery of said carrier.
7. In a check writing machine the combination of a casing, a rotatable carrier mounted thereon having the shape of a segment of a cylinder, type bars mounted in the curved surface of said segment for movement parallel with the axis thereof, a platen for engagement with the type forms of said bars, the type bars being movable to bring various lines of type selectively into line with said platen, a keyboard mounted on the flat side of said carrier, and a series of movable pointers or indexes on said keyboard, one for each of said type bars.
8. In a check writing machine the combination of a casing, a rotatable carrier mounted thereon, having a curved surface and a flat surface forming, substantially, in shape, a segment of a cylinder, type bars mounted to move along the curved surface, index pointers mounted to move along the flat surface, and a yoke connecting each type bar to each index pointer.
9. In a check writing machine the combination of a casing, a rotatable carrier mounted thereon having a curved surface and a flat surface forming, substantially, the shape of a segment of a cylinder, type bars mounted to move along the curved surface, index pointers mounted to move along the flat surface, and a yoke connecting each type bar to each index pointer, said yoke having its connection with the type bar adjustable longitudinally to justify the position of the pointer and its type bar with relation to each other.
10. In a check writing machine a type bar therefor, said type bar comprising a carrying plate and a type plate fastened thereon, said carrying plate having down turned ends, a rod mounted between said ends, supporting means permitting longitudinal movement of said bar, and operating means connected to said rod for effecting said movement of the type bar.
11. In a printing apparatus, an indicating dial; a type carrying bar having angularly disposed ears; supporting means permitting longitudinal sliding movement of said bar; a rod supported in said ends; a yoke connected to said rod; adjustable means for regulating the relation between the yoke and rod and thereby the type carrying bar; a pointer connected to said yoke and cooperating with said dial; and operating means connected to said yoke for effecting said movement of the type bar.
12. In a check writing machine a type bar therefor, said type bar comprising a carrying plate and a type plate fastened thereon, said carrying plate having down turned ends, a rod mounted between said ends, a yoke connected to said rod, and a pointer connected to said yoke.
13. In a check writing machine a type bar therefor, said type bar comprising a carrying plate and a type plate fastened thereon, said carrying plate having down turned ends, a rod mounted between said ends, and a yoke connected to said rod, a pointer connected to said yoke, said yoke being adjustable longitudinally on said rod.
14. In a check writing machine the combination of a casing, a rotatable carrier mounted thereon, said carrier having the shape of a segment or a sector of a cylinder, a base plate below said carrier, a roller platen supported by said base plate and actuating means for moving said platen to and from position to cooperate with the cylindrical surface of said carrier during the revolution of the latter.
15. In a check writing machine the combination of a casing, a rotatable carrier mounted thereon, said carrier having the shape of a segment or a sector of a cylinder, a base plate below said carrier, a roller platen supported by said base plate and movable toward and from said carrier, type bars mounted to slide on said carrier for the purpose of placing different type forms in line with said platen and making contact therewith on the rotation of the carrier.
16. In a printing apparatus, a work bed; a substantially cylindrical type carrier having a flattened portion on one side thereof and supported above said bed for rotation about its cylindrical axis; selecting means including indicating means on said flattened portion of the carrier for bringing the type on said carrier selectively to printing position; a platen on said work bed for coaction with the selected type during rotation of the carrier; a holding device for holding the carrier in starting position with its flattened side adjacent the platen to permit insertion of the work therebetween; and operating means for rotating the carrier to print and feed the work.
17. In a printing apparatus, a work bed; a substantially cylindrical rotatable carrier above said bed, having a flattened portion on one side thereof; a plurality of type on

the cylindrical surface of the carrier movable selectively to printing position; selecting means including indicating means on the flattened portion of the carrier for bringing said type to printing position; a platen on said work bed for coaction with selected type during rotation of the carrier; a holding device for holding the carrier with said selecting means in operative position; a second holding device for holding the carrier in starting position with its flattened portion adjacent the platen to permit insertion of the work; and operating means for rotating the carrier to print and feed the work.

18. In a printing apparatus, a work bed; a rotary platen in said bed; a substantially cylindrical, rotatable type carrier above said bed, having a flattened portion on one side thereof; a plurality of type supporting members on the cylindrical surface of the carrier, each movable to bring a plurality of type forms, selectively, to position for coaction with the platen; selecting means including indicating means on the flattened portion of the carrier for selecting said type; and operating means for rotating the carrier and bringing the selected type forms into rolling coöperation with the platen to print and feed the work.

19. In a printing apparatus, a rotary platen; a rotary type carrier having substantially the form of a segment of a cylinder with a curved portion and a flattened portion; a plurality of series of type forms on said curved portion, each series being movable axially of the carrier to bring its forms selectively to position for coöperation with the platen; and a cam on said carrier and coöperating means connected to said platen for raising and lowering the platen as each selected type form approaches and leaves the platen, respectively, during the rotation of the carrier.

45 20. In a printing apparatus, a rotary platen; a rotary type carrier having substantially the form of a segment of a cylinder with a curved portion and a flattened portion; a plurality of series of type forms on said curved portion, each series being movable axially of the carrier to bring its forms selectively to position for coöperation with the platen; selecting means on said flattened portion of the carrier for effecting said selective movement of the type forms; and a cam on said carrier and coöperating means connected with the platen for moving the platen to and from active position as each selected type form approaches and leaves the platen, respectively, during the rotation of the carrier.

21. In a printing apparatus, a rotary platen; a rotary type carrier having substantially the form of a segment of a cylinder; a plurality of series of type forms on

the cylindrical portion of the carrier, each movable to bring its forms, selectively, to position for coaction with the platen; and actuating means connected with the carrier and with the platen for moving the latter to and from active position as each selected form approaches and leaves the platen respectively during the rotation of the carrier.

22. In a printing apparatus, a rotary platen; a rotary type carrier having substantially the form of a segment of a cylinder; a plurality of series of type forms on the cylindrical portion of the carrier; each movable to bring its forms selectively to position for coaction with the platen; a cam connected with the carrier, and a cam follower connected with the platen, said cam being designed to move the platen to and from active position as each selected form approaches and leaves the platen respectively during the rotation of the carrier.

23. In a printing apparatus, a rotary platen; a rotary type carrier having substantially the form of a segment of a cylinder; a plurality of series of type forms on the cylindrical portion of the carrier, each movable to bring its forms selectively to position for coaction with the platen, and each having its type forms arranged with their terminations in alignment axially of the carrier; and a cam connected with the carrier and a coöperating follower connected with the platen, said cam having a working outline designed to actuate the platen through said follower to and from active position as each selected type form approaches and leaves the platen respectively during the rotation of the carrier.

24. In a printing apparatus, a carrier having a printing movement and provided with a plurality of type forms spaced from and in alignment with each other; a rotary platen for successive coöperation with the type forms during the printing movement of the carrier; and actuating means for moving the platen to inactive position as the end of each type form approaches the platen, including adjustable means for advancing or retarding said movement of the platen.

25. In a printing apparatus, a rotary platen; a carrier provided with a plurality of type forms and having a printing movement to carry said forms by the platen and also a return movement to restore said carrier to position; actuating means for moving the platen to active position during said printing movement of the carrier and for retaining the platen in inactive position during said return movement of the carrier, and manipulative means for connecting the platen mechanism and actuating means after the return movement of the carrier.

26. In a printing apparatus, a rotary platen; a carrier provided with a plurality of type forms and having a printing move-

- ment to carry said forms by the platen and also a return movement to restore said carrier to position; actuating means for moving the platen to active position during said printing movement of the carrier adapted to retain the platen in inactive position during said return movement of the carrier; and manually operative means for moving the platen to active position during said return movement of the carrier.
27. In a printing apparatus, a rotary platen; a carrier having a printing movement and a return movement, and provided with type forms in alinement and spaced from each other in the direction of printing movement; and actuating means for moving said platen to and from active position as each type form approaches and leaves the platen, respectively, during said printing movement of the carrier, said actuating means being adapted to retain the platen in inactive position during said return movement of the carrier.
28. In a printing apparatus, a rotary platen; a carrier having a printing movement and a return movement, and provided with type forms in alinement and spaced from each other in the direction of printing movement; actuating means for moving said platen to and from active position as each type form approaches and leaves the platen, respectively, during said printing movement of the carrier, said actuating means being adapted to retain the platen in inactive position during said return movement of the carrier; and manually operative means for moving the platen into coöperation with the type forms during the return movement of the carrier.
29. In a printing apparatus, a rotary platen; a carrier having a printing movement and a return movement, and provided with type forms in alinement and spaced from each other in the direction of printing movement; a cam connected with the carrier and a cooperating follower connected with the platen for moving the platen to and from active position as each type form approaches and leaves the platen respectively, during said printing movement, said follower being adapted for movement to inactive position by said cam during said return movement; and means for retaining said follower in active position during said return movement.
30. In a printing apparatus, a rotary platen member having its impression surface formed to score the work; a type carrier having a printing movement to bring its type forms into rolling coaction with the platen; and operating means for effecting said printing movement of the carrier and for rotating said platen at a surface speed different from that of the type forms for scoring one side of the impression.
31. In a printing apparatus, a type carrier having a printing movement and a rotary platen for coaction therewith, the impression surface of which is provided with circumferentially extending alternating projections and depressions and with teeth for scoring the work.
32. In a printing apparatus, a type carrier having a printing movement, and a rotary platen for coaction therewith driven at a surface speed different from that of the type forms and formed with projections pitched circumferentially of the platen for scoring the work.
33. A check writing machine comprising means to emboss a check with characters and means to face off from the check a part of the raised portions of these characters.
34. In a check writing machine the combination of a carrier having type thereon, a platen adapted to bear against said type, teeth on said carrier, a member connected to said platen and operated on by said teeth to raise said platen against said type and hold it up during fixed intervals, and means for varying the thickness of said member to increase or shorten the length of said intervals.
35. In a check writing machine the combination of a carrier having type thereon, a platen for coöperation with said type, a lever on which said platen is carried, teeth on said carrier, a pawl connected to said platen lever and operated on by said teeth to raise said platen against said type and hold it up during fixed intervals, and means for varying the thickness of the pawl to hasten or retard the lifting of said pawl.
36. In a check writing machine the combination of a base, a carrier mounted to move above said base, a pin extending up through said base, said pin being adapted to hold a check in position on said base, a roller platen adapted to raise a part of said check against said carrier to be printed thereby, and means operating to pull down the pin and raise the platen on the movement of the carrier to print the check.
37. In a printing apparatus, a work support; a type carrier, a platen coöperating with the type on said carrier to impress the work; a presser foot serving as a gage for the location of the work on said bed and also as a means for restraining movement of the work; and means for moving said presser foot to inoperative position upon commencement of a printing operation.
38. In a printing apparatus, a work support; a type carrier; a platen coöperating with the type on said carrier, said carrier and platen having a relative impressing movement; a stop serving as a gage for the location of work on said bed and also as a means for restraining movement of the work; and operating means for effecting said printing movement of the carrier and

platen and moving said stop to inoperative position.

39. In a printing apparatus, a work support; a type carrier; a rotary platen for cooperation with the type on said carrier, said carrier having a printing movement to impress and feed the work; a stop for restraining movement of the work; a spring for holding said stop normally in active position; and operating means for effecting said printing movement of the carrier and platen, and holding said stop in inactive position during said printing movement of the work.
40. In a machine of the class described, the combination with a rotatable type carrier, of a platen movable toward and from the type carrier, devices whereby rotation of the type carrier in one direction will move the platen toward the type carrier whereby to

print and feed the work, means whereby rotation of the type carrier in the other direction will disable the platen moving means, and manipulative means for enabling the platen moving means preparatory to movement of the carrier in the first mentioned direction.

41. In a check writing machine, the combination with a casing, of a carrier mounted to rotate thereon, said carrier having substantially the shape of a half cylinder providing a flat top and a round bottom, type bars adjustably mounted on said round bottom, manipulative devices on the flat top controlling the adjustment of the type bars and means connecting the manipulative devices and the type bars.

In testimony whereof I affix my signature.
ARTHUR C. LA MAY.
